UNITED STATES PATENT OFFICE.

E. B. WHITE, OF NASHUA, NEW HAMPSHIRE.

ALARM ATTACHMENT FOR TILLS.

Specification of Letters Patent No. 24,685, dated July 5, 1859.

To all whom it may concern:

Be it known that I, E. B. WHITE, of Nashua, in the county of Hillsboro and State of New Hampshire, have invented 5 a new and Improved Alarm Attachment for Tills; and I do hereby declare that the following is a full, clear, and exact description of the same, reference being had to the annexed drawings, making a part of 10 this specification, in which—

Figure 1, is a vertical section of my invention applied to a till, x, x , Fig. 3, indicating the plane of section. Fig. 2, a vertical section of ditto, taken in the line y, y , Fig. 3. 15 Fig. 3, a plan or top view of ditto. Fig. 4, a detached plan view of the bell-striking mechanism.

Similar letters of reference indicate corresponding parts in the several figures.

20 This invention consists in the employment or use of a series of bolts placed within a hinged plate which is connected with a bell-striking mechanism and arranged with keys, substantially as hereinafter described, whereby a person unacquainted with the position of the parts cannot open the drawer or till without sounding an alarm, the parts admitting of change or permutation, so that if their position should 25 casually become known to others than the proper persons, they may with the greatest facility be so arranged as to cause different keys to be acted upon in order that the till or drawer may be opened without actuating 30 the bell-striking mechanism.

To enable those skilled in the art to fully understand and construct my invention I will proceed to describe it.

A, represents a till or drawer which may 40 be of usual construction, and B, is a metal case or box which may be of rectangular form and of any suitable size attached to the inner side of the front board a , of the drawer at about its center.

45 The front or outer side of the box B, is formed of a plate b , the lower part of which is attached to the box by a joint c , which may be formed of a rod passing through eyes attached to the box and plate. The 50 plate b , is cast with a series of vertical sockets d , at its inner side—four are represented in Fig. 3, but more or less may be used. In each socket d , a bolt C, is placed and allowed to slide freely. Each bolt resting on a spiral spring e , which has a tendency to keep it elevated and behind a metal

ledge or stop D, attached to the board or plate f , above the drawer as shown clearly in Fig. 1.

The upper part of the bolt plate b , at one end is attached by a link g , to a lever h , which has its fulcrum at i , as shown clearly in Fig. 2. To this lever h , one end of a bar j , is attached. This bar j , is equal in length to the bolt plate b , and has an arm on its opposite end which is fitted on a rod which forms the fulcrum i , of the lever h .

On the rod i , a series of keys k , are fitted. The lower ends of these keys project below the bottom of the drawer through an opening l , therein. The upper parts k' , of the keys k , are at right angles to the lower parts and each part k , projects over a lateral projection m , attached to each bolt C. Each projection m has a notch n , made in it as shown clearly in Figs. 1 and 2. The use of these notches will be presently explained.

In the lower part of the box B, at one side, a plate o , is fitted loosely on a pintle p . This plate o , has a pin q , projecting from one side of it—directly behind the lower end of the lever h , as shown clearly in Fig. 2, and a spiral spring r , is attached to the plate o , and also two bell hammers E, E, by rods s, s .

F, is a bell which is attached to the bottom of the till or drawer, the hammers E, E, being within it.

Within the box B, a socket t , is placed or formed. This socket contains a spiral spring u , on which a plunger v , rests the bar j , bearing on said plunger. See Fig. 1.

On the upper part of the box B, a sliding plate G, is placed. This plate has a ledge w , on its upper surface and a spiral spring a' , bears against a pendent b' , at its under side, said spring having a tendency to keep the plate G, over the top of the bolt plate b , as shown in Fig. 2. Behind each key k , a spiral spring c' , is placed.

From the above description it will be seen that when the till or drawer A, is closed the bolts C, would all be forced up behind the ledge or stop D, by the springs e , if not retained in downward position and consequently if the till or drawer A, should be pulled outward the bolt plate b , would also be forced outward and the lever h , would actuate the plate o , and consequently the bell hammers E, E, would strike the bell by 105 the action of the spring r , and sound an alarm. In this case therefore no person

could open the till without sounding the bell, but in order to allow certain persons to open the till without noise a certain number of the bolts are secured down by screws d' , 5 and through the upper part k' , of each key k , that is opposite a depressed bolt a screw e' , passes, said screws bearing on the plate j . The parts k' , of the keys opposite the bolts C' , that are not retained in a down- 0 ward position have their screws e' , removed.

By referring to Fig. 3, it will be seen that the bolts C , numbered 1 and 2 are not secured down as the screws e' , of the parts k' , of their keys are removed. Consequently 5 by pressing outward with the fingers the lower ends of the keys k , that correspond with the bolts 1, 2, said bolts will be depressed in consequence of the parts k' , of said keys acting on their projections m , and 10 the till or drawer may be opened or drawn outward without sounding the bell. A person however, even if having a knowledge of the mechanism of the device but ignorant as regards which bolts C , are secured down 15 could not open the till without detection, for if a key k , be actuated that is not opposite or does not correspond with a bolt C , that is free or not secured down in its socket, the screw e' , of said key will actuate the bar j , 30 and consequently the lever h , and the bell will be sounded.

It will be seen that the device admits of a variety of changes as either of the bolts C , may be secured down, and any number of 35 them. When one bolt C , is secured down or depressed, the device admits of four changes, with two bolts depressed. Six changes, with three bolts depressed, four changes and all the bolts free or loose constituting another 40 change, fifteen changes in all with four bolts.

The plate G , is used to cover the bolt plate b , when the till is opened so that the bolts will be concealed. This is essential for if the bolts were exposed an observer might 45 notice which bolts were secured down in the bolt plate and thereby be enabled to open the drawer without sounding the alarm. This plate G , is shoved back as the till is closed in consequence of coming in contact 50 with a ledge f' , at the bottom of the stop D , so that the free or loose bolts C , will not be prevented from rising. See Fig. 1. The plate G , is thrown over the top of the bolt plate b , by the spring a' , as the till is opened.

55 The spring u , in the socket t , is used so

that each key k , will offer the same resistance to the touch. This is essential for if the bar j , did not rest or bear on this spring a person might detect by the sense of feeling these keys which operate the free or loose 60 bolts, as the latter keys depress the bolt springs e , and the former would not have any spring to resist their movement and would consequently move comparatively free. The employment of the spring u , in 65 the socket t , effectually prevents any such result. The notches n , in the lateral projections m , serve to catch the ends of the upper parts k' , of the keys so that when the bolt plate b , is moved outward in endeavoring 70 to open the till, the keys k , are prevented from operating on the bolts and the device therefore cannot be tampered with but must be moved back to a closed state before another trial can be made and consequently 75 another alarm will be sounded if a second essay is made to open the till.

The screws d' , are covered by a plate g' , to conceal them for the same reason that the bolts C , are concealed by the plate G . 80

Having thus described my invention what I claim as new and desire to secure by Letters Patent, is,

1. The bolt plate b , provided with bolts C , connected by a joint c , to the box B , and 85 connected to a bell-striking apparatus, substantially as shown in connection with the keys k , and a stop D , the whole being applied to the till substantially as and for the purpose set forth. 90

2. In combination with the bolt plate b , bolts C , and keys k , the bar j , and screws e' , in the parts k' , of the keys, when the bolt plate and bar j , are both connected with the lever h , or to the bell-striking apparatus in 95 any proper way.

3. The employment or use of the sliding plate G , combined and arranged with the bolt plate b , and stop D , to operate automatically as and for the purpose set forth. 100

4. The employment or use for the purpose specified of a supplemental spring u , fitted in a socket t , or otherwise arranged to resist the movement of the bar j , when said bar j , is used in connection with spring bolts C , 105 substantially as described.

E. B. WHITE.
